UNITED STATES PATENT OFFICE.

HERBERT H. ILLCH, OF NEW YORK, N. Y.

DETACHABLE SHIELD.

1,332,126.

Specification of Letters Patent. Patented Feb. 24, 1920.

Application filed July 1, 1919. Serial No. 308,027.

To all whom it may concern:

Be it known that I, HERBERT H. ILLCH, a citizen of the United States, and a resident of the city of New York, borough of 5 Manhattan, county of New York, and State of New York, have invented a new and Improved Detachable Shield, of which the following is a full, clear, and exact description.

10 This invention relates generally to a shield, and relates more particularly to a shield adapted to be independently removed.

While it is not broadly new to provide 15 a detachable shield, the constructions heretofore suggested have been complicated and cumbersome and have required the use of many parts in order to position the same with respect to another body.

20 One of the objects of this invention is to provide a self-contained shield of simple construction which may be conveniently and readily applied to another wind shield when used in connection with an automobile, so that the shield will serve to protect 25 the eyes of the driver from the reflection of bright rays, and in rainy weather to furnish a protecting shield which will keep a portion of the glass clean and protect it 30 from the rain.

A further object of this invention is to provide a detachable shield having an adjustable means thereon whereby the shield may be readily applied to wind shields arranged at different angles.

Another object of this invention is to provide a shield having downwardly extending side portions and an adjustable means associated therewith so that the angle of the 40 shield relative to the body on which it is supported, may be varied at will and still maintain a complete closure for the side thereof. A further object of this invention is to provide a shield having an integral 45 extension portion shaped to form a yielding spring connector which may be used to hold the shield in its proper position.

The above objects are accomplished by providing a wind shield preferably formed 50 in one piece of a transparent material the said shield comprising a main panel and an integral portion extending outward from the main panel between the side portions and being bent to form a substantially 55 closed loop open at one side, so that the

upper edge of a wind shield or other body may be inserted therein whereby the said loop functions as a resilient holding means. An adjustable means is provided, associated with the downwardly extending side 60 portions, so as to form a complete closure for the said sides at all times irrespective of the angle between the main panel of the shield, and the panel of the wind shield or other body on which the detachable shield 65 is mounted.

Other objects and advantages will be apparent from the following specification and the accompanying drawings in which similar reference characters designate like parts 70 in the several views.

In the drawings showing one of the preferred forms of this invention Figure 1 is a broken elevation view showing an automobile wind shield with the detachable 75 shield fixed on the top thereof.

Fig. 2 is a sectional view taken on the line 2—2 of Fig. 1.

Fig. 3 is a sectional view of the shield showing the position of the bent loop when 80 the shield is detached from the body on which the detachable shield is associated.

Fig. 4 is a sectional view of the wind shield showing the application thereof to a wind shield panel which is carried at an 85 angle, and the downwardly extending side portions of the detachable shield being provided with a means for forming a complete closure for the sides at all times irrespective of the angle of the detachable shield. 90

Fig. 5 is a sectional view taken on the line 5—5 of Fig. 4.

In the drawings showing one of the preferred forms of the invention the detachable shield is preferably composed of 95 any suitable transparent material such as celluloid, and is preferably formed as an integral structure made of one piece of material bent to form a main panel 1 which may be of any suitable size, and downwardly 100 extending side portions 2, 3. A projecting portion of the material 4 extends from between the side portions 2, 3, and is bent to form a substantially closed loop 5, the said loop in turn being bent upward about the 105 rear edge 6 of the panel 1 so that the long axis of the loop is in a substantially vertical plane. When in this position, one end 7 of the loop extends downwardly and inwardly of the shield, as shown in Fig. 3. When so 110

formed, an opening 8 is formed at the lower end of the loop, so that the detachable shield may be held in position in front of a window panel 9 of a wind shield or other body by 5 with-drawing the end 7 of the loop and passing the top edge 10 of the wind shield through the opening 8 of the loop. After the shield is properly positioned, the top portion of the loop will rest upon the top 10 edge of the wind shield, the edge 6 of the detachable shield contacting with the front of the wind shield 9, and the end 7 of the shield will contact with the opposite side of the wind shield at a lower bend. In the preferred form shown, a resilient cushion 11 composed of rubber or other suitable material, is interposed between the wind shield 9 and the end 7 of the shield, the said cushion 11 being secured to the end 7 by an adhesive 15 material or other suitable material. In Fig. 2, the top frame 10 of the wind shield is separated from the glass panel 9 of the wind shield by a suitable cushion 12 of rubber or other suitable material.

20 25 In Fig. 4 the shield is shown as applied to the upper portion of a wind shield 9 which is carried at an angle. There is shown associated with the downwardly extending side portions of the shield, a means 30 for forming a complete closure for the sides, irrespective of the angle between the main panel 1 and the wind shield 9. The said means is shown as comprising the slide 13 pivotally connected to the upper portion of 35 the sides 2 adjacent the edge 6. In the form shown, the slide 13 is triangular in shape, one edge 14 thereof preferably being provided with a strip of rubber 15 or other suitable material so as to form a 40 water-tight joint with the panel of the wind shield 9. The strip 15 would further attempt to eliminate the noise and chatter. As a means of holding the slide 13 in a fixed position relative to the downwardly projecting sides 2 the slide 13 in the preferred 45 form is provided with a slot 16, and a threaded screw 17 is fixed in the side 2, and passes through the slot 16, and a wing nut 18 threaded on the screw 17 serves when 50 tightened to hold the slide 13 in any predetermined adjusted position relative to the downwardly extending side 2. Of course, it is understood that an arrangement similar to that shown in the figure in 55 connection with the downwardly extending side 2 will be duplicated on the other downwardly extending side 3. It is to be understood that any other suitable means may be provided for holding the slide 13 in any adjusted position relative to the side 2. By 60 providing an adjustable means such as that above described, it is seen that the detachable shield may be applied to a wind shield carried at an angle, or the panel 1 may be 65 angularly adjusted relative to the wind

shield panel 9, and in either of these cases a closure is formed for the side portions, so that if it rains, the water is prevented from finding its way under the shield thus preserving at all times a clear field of vision 70 for the driver.

An important feature to be noted is that there is formed at all times a water-tight connection at the upper edge 6 of the panel 1 of the detachable shield, and that by providing the extending portion of the panel 1 which is shaped in the form of a loop, a very simple but yet effective spring or yielding connection is provided which will readily adjust itself to the various angular 75 positions assumed by the detachable shield, and further provides a connection which may be applied to the tops of wind shields of various sizes and forms. It is further to be noted that when applied to the top of 80 a wind shield the inner surface of the loop contacts with the shield at certain points 18 and 19, the remaining portion of the loop being spaced from the top of the shield thus permitting the spring action of the 85 bent loop portion to be effected to securely hold the detachable shield in position.

It is thus seen that there is herein provided a detachable shield of simple construction which is readily adapted to be adjusted to different angles and to be used in connection with supports of varying forms and sizes, the said shield being so formed that under all of the above conditions of use, it effectively functions to preserve at all 90 times including rainy weather, a clear field of vision for the driver.

This invention is not to be limited to the form of bend as shown, but is intended to cover a construction having an integral extension shaped and formed to receive a member therein, and to effectively exert a spring pressure in connection therewith to properly hold the shield in position. It is further to be understood that a shield of this character 105 has various uses, and is not to be limited to a wind shield as shown, but it is obvious that it may be used on trolley cars, locomotives, or wherever a detachable shield of this character may be needed to protect the eyes 110 from glare or to furnish a clear vision through a glass in stormy weather.

While there has herein been shown certain forms of this invention, it is understood that changes and modifications may be made 115 without departing from the spirit and scope of this invention.

Having thus described my invention, what I claim as new, and desire to secure by Letters Patent is:

1. A detachable shield comprising a main transparent panel of celluloid or similar material, downwardly extending side portions integral therewith, and an extension formed integral with and as a continuation 125 130

of the panel portion and bent to form a spring loop, whereby a continuous water tight construction is formed.

2. A detachable shield comprising a main panel, downwardly extending sides integral therewith, a spring loop formed integral with and as a continuation of the said main panel portion whereby a continuous water tight construction is formed throughout the width of the main panel at the spring loop, and an adjustable means associated with the downwardly projecting portions, to maintain a complete closure therefor irrespective of the angular position of the main panel.

3. A one-piece detachable shield of celluloid or similar material comprising a main panel, downwardly extending sides, and a projecting portion integral with the main panel and formed as a continuation thereof bent in the form of an open loop, to form a spring member adapted to fit over another wind shield.

4. A one-piece detachable shield of celluloid or similar material comprising a main panel, downwardly extending sides, a projecting portion bent in the form of an open loop adapted to fit over the top of another shield, and an adjustable slide pivotally connected to the downwardly extending sides for maintaining a complete closure irrespective of the angular position of the main panel.

5. The combination of a wind shield, and a detachable shield adapted to be positioned on the top thereof comprising a main panel, downwardly extending side portions integral therewith, and a continuous extension portion integral with and extending

throughout the width of the panel bent to form a spring loop which may be positioned over the top of the wind shield to hold the detachable shield in position relative thereto, whereby a water tight construction is formed throughout the width of the main panel at the spring loop.

6. A detachable shield adapted to be positioned on a wind shield, comprising a main panel of celluloid or similar transparent material, a continuous flexible connector integral therewith for connecting the said shield on the wind shield, downwardly extending side portions connected with the panel and adjustable slides pivotally connected with the side portions and means for holding said pivoted slides in adjusted position for forming a substantially complete closure at the sides of the detachable shield at all times irrespective of the angular relation of the main panel relative to the wind shield.

7. A detachable shield adapted to be positioned on a wind shield, comprising a main panel, a flexible connector integral therewith for connecting the said shield on the wind shield, downwardly extending side portions connected with the panel and adjustable means associated with the side portions for forming a substantially complete closure at the sides of the detachable shield at all times irrespective of the angular relation of the main panel relative to the wind shield, said adjustable means including a slide connected to the side piece, and means for securing the slide and the side in a predetermined position.

HERBERT H. ILLCH.
